UNITED STATES PATENT OFFICE.

C. R. FRINK, OF NORWICH, NEW YORK.

IMPROVEMENT IN HAY-SPREADERS.

Specification forming part of Letters Patent No. **59,001**, dated October 23, 1866.

To all whom it may concern:

Be it known that I, C. R. FRINK, of Norwich, in the county of Chenango and State of New York, have invented additional Improvements in my Hay-Spreading Machine for which Letters Patent were issued the 8th day of May, 1866; and I do hereby declare and make known that the following is a full, clear, and exact description of the construction and operation of the same, reference being had to the accompanying drawings, making a part of this specification, in which—

Figure 1 is a perspective view of my hay-spreading machine with my additional improvements connected therewith. Fig. 2 is a view in detail of bracket, a series of which support the shafting and frame-beam of the machine; Fig. 3, view in detail of an eccentric grooved wheel or disk, showing the fork-rods with spiral springs around them and the connection of the rods with the wheel by a box and plate; Fig. 4, vertical section of wheel or disk and of the plate fitting around in the groove of the wheel, as well as section of box in which the fork-rods operate.

Like letters in the different figures of the drawings indicate like parts.

My additional improvement or invention relates to the substitution of eccentric grooved wheels or disks on the extreme rear shaft instead of the cranks, as in the old machine, the grooves of said wheels or disks being provided with plates fitting around therein and thereon, which plates, terminating in the form of boxes, by the addition of other plates thereto, by means of bolts and screw-nuts, receive the fork-rods through apertures constructed in the same, the said fork-rods having spiral springs surrounding them, which springs extend from the coil of the forks to the under sides of the boxes, to which they are permanently attached, whereby, from the eccentric motion given to the wheels or disks from the revolution of the shaft when the machine is in operation, the fork-rods are caused to assume a vibratory and upward motion when passing over uneven ground, the springs, as is obvious, when compressed, returning the fork-rods to their original position.

The eccentric wheels or disks are found to

be less liable to get out of order, and will not bend or break, as is sometimes the case with the cranks and connecting-rods of the old machine. They are lighter and give the forks a more perfect action, particularly when the ground is broken or uneven.

My invention also relates to that part of the arms of the brackets which support the extreme rear shafts.

Instead of constructing them whole or solid, as in the old machine, I construct the arms independently of the brackets, and join them thereto by means of pivots.

The advantage of the jointed arms is that, when the machine is passing over broken ground or descending steep hills or over ditches, where the weight of the machine is liable to rest on the forks, the arms, as thus jointed to the brackets by the pivots, are permitted to rise upward, and thus relieve the forks from any pressure that may be produced from the irregularities above mentioned.

To enable any one to understand my improvements more fully, I will proceed to describe and indicate the same by letters of reference, and such parts as are not new, but which necessarily serve to illustrate understandingly their connection with the improvements.

A is the eccentric wheel or disk, (see Fig. 3,) constructed with a groove around its rim. In other words, the wheel may be termed a "double-flanged wheel."

Fitting around the wheel, between the flanges, and flush with the edges thereof, is a plate, which plate is so constructed when passed around as to terminate in a short straight bar like form a. (See Fig. 4.) Two semicircular grooves are made on the face side of this bar. The two rods B of the fork, having spiral springs C around them, are placed within these grooves. A cap-plate, b, having corresponding grooves, is then placed over the rods, thus forming perfect circular holes, which are of a sufficient size to permit a free and easy movement to the rods therein. The cap-plate is fastened securely to the bar by screw-bolts and nuts e, the passing of the plates around in the grooves of the wheels and the attachment of the cap-plates thereto constituting boxes for the fork-rods to operate in. The con-

nection of the plates with the wheels or disks is such that a free and easy movement is permitted to either in their operation.

A series of these eccentric wheels and their connections, as above described, are permanently attached to the extreme rear shaft at suitable points along the same. (See Fig. 1.) The fork-rods are then connected in a suitable manner to the lever-rods C', attached to the rear of the frame-beam D of the machine.

The arm E is constructed (see Fig. 2) and joined to the bracket F in a proper manner by pivots d. A series of these brackets, with the improved arms connected therewith, are attached to the frame-beam of the machine, (see Fig. 1,) and, as herein remarked, support the shafting.

The effect of the irregularities of the ground upon the arms through the forks, as mentioned, is represented in red lines in Fig. 2, by the arm being thrown up.

Having thus fully described my invention, what I claim therein as new, and desire to secure by Letters Patent, is—

1. The grooved or double-flanged eccentric wheel or disk A, combined with a movable plate, a, and cap-plate b, for operating the fork-rods B, in their connection with the spiral springs C, substantially in the manner and for the purpose as herein set forth.

2. The movable jointed arms E, in combination with the brackets F, for relieving the forks of any straining or undue pressure, substantially in the manner and for the purpose as herein described.

C. R. FRINK.
